TENSION-MAINTAINING DEVICE FOR CRANES AND THE LIKE

Hellmut Ernst, Rudolf Zapp, and Ernst Kropik, Nurnberg, Germany, assignors to M.A.N. Maschinenfabrik Augsburg-Nurnberg AG, Nurnberg, Germany

Application February 18, 1957, Serial No. 640,842

7 Claims. (Cl. 254—172)

The present invention relates to a tension maintaining device for cranes and the like, and more particularly to such a device which is secured to a downwardly directed end of the crane lifting line to exert a pulling force on the lifting line whenever said line tends to become slack.

It is the principal object of this invention to provide an inexpensive tension maintaining device for cranes and the like, which requires a minimum of space and may be installed on existing cranes.

It is another object of this invention to provide a tension maintaining device for cranes and the like which becomes effective immediately on any slackening of the lifting line.

It is a further object of this invention to provide a tension maintaining device for cranes and the like which requires relatively low forces to prevent the occurrence of slack in a crane lifting line.

It is an additional object of this invention to provide a tension maintaining device for cranes and the like which essentially comprises a weight which readily descends under the action of gravity when any slack occurs but is immediately braked against upward movement when the lifting line is lifting a load.

It is still another object of this invention to provide a tension maintaining device for cranes and the like wherein a tension element will pull said lifting line to maintain said lifting line taut whenever the force exerted by a load on said lifting line is suddenly decreased.

Other objects and advantages of this invention will become apparent upon reference to the accompanying description when taken in conjunction with the following drawings wherein—

Figure 1 is a side elevational view of an embodiment of the tension maintaining device of this invention employing a hydraulic brake with a portion of the brake shown in section; and

Figure 2 is a view similar to Figure 1, which shows another embodiment of the invention wherein a tension winch is substituted for the tension weight and hydraulic brake of the Figure 1 embodiment.

The tension maintaining device as disclosed in this invention was originally devised for operation on stripper cranes in steel works. In steel making, stripper cranes are used for transporting ingots and molds in which the ingots are cast. When equipped with a tong head having a pressure piston, stripper cranes are also used for removing the ingots from the molds after they have become set.

In the ingot removing operation, the mold is seized by the tongs of the tong head while the piston exerts a force against the ingot. One end of the mold is set upon a surface so that when the ingot emerges from the mold, the ingot will be in contact with the surface and will not be dropped upon a surface. The mold, however, will be quickly jerked upward because of the release of the ingot from the mold. The upward movement of the tongs will cause a sudden slackening of the lifting line which suspends the tong head.

Slack also can occur in stripper and other types of

2

cranes when the load on the crane is being lowered to a surface and reaches the surface before the crane operator has stopped the continuing downward movement of the crane line upon which the load is suspended.

- 5 The sudden slackening of the crane lifting line results in a whipping of the line which is dangerous since it may cause damage to equipment within the plant or may result in injury to operating personnel. In addition, the sudden forces exerted upon the whipping lifting line cause 10 a gradual weakening of the line which greatly decreases the operating life of the line. The expense involved in frequent replacement of the lifting line is undesirable, since it adds greatly to the operating costs of the crane.

The present invention comprises a tension maintaining 15 device for a crane line and prevents the occurrence of slack in the crane line by exerting a pulling force upon the line. This device essentially comprises a tension weight attached to a braking device. The tension weight is secured to a downwardly directed end of the lifting 20 line of the crane after it has passed over the lifting pulley block and idler pulleys. The occurrence of any slack in the lifting line will cause an immediate downward movement of the tension weight, under gravity, to exert a pulling force on the lifting line to eliminate the slack. 25 However, whenever a force is exerted upon the line by the lifting of the load by the line, the upward movement of the weight is braked by a hydraulic cylinder or a tension winch. Both of the embodiments comprising the hydraulic braking cylinder and the tension winch will 30 be described.

Referring now to Figure 1 wherein like reference symbols indicate the same parts throughout the various views, 1 indicates the frame of an overhead traveling crane having a lifting drum 2 thereon. A crane lifting line 3 has one end wound around the lifting drum and the other end passing around a pulley 4 in the lifting block 5 which has a transverse bar 5A to which a tong head may be attached. The line then passes upwardly over an idler pulley 6 and then downwardly so that the downwardly directed end 7 of the lifting line is connected to a tension weight 8. The tension weight 8 is normally in contact with a resilient buffer stop 9 which is mounted on the lower surface of the frame 1.

The other end of the tension weight 8 is connected to 45 a hydraulic brake, generally indicated at 10, which is mounted upon structure extending from the overhead frame 1. The brake 10 comprises a piston rod 11 one end of which is connected to the tension weight 8 and the other end is connected to a piston 12 which reciprocates within a brake cylinder 13. Check valves 14 are provided in the piston 12.

The brake cylinder 13 is open at both the upper and lower ends, as indicated at 15 and 16, respectively, and has a conduit 17 which provides communication between 55 both ends of the brake cylinder. The conduit 17 has a check valve 18 therein. The check valve 18 is operable in the same direction as the check valves 14. The open end 16 of the brake cylinder is connected through a conduit 19 to a balancing chamber 20 which is open to the 60 atmosphere. The balancing chamber, conduits and the brake cylinder are filled with a hydraulic fluid indicated at 21 to the level as shown in Figure 1.

Mounted upon the piston rod 11 is an actuator arm 22 which engages a switch 23 which is connected with 65 the operating circuit of the lifting drum 2. The switch 23 is actuated by increasing slack in the lifting line which causes the tension weight to descend beyond the switch 23. Actuation of the switch will disengage the lifting drum from its operating circuit to prevent additional slack forming in the lifting line.

With the above description of the embodiment of the

invention in mind, the operation of a tension maintaining device will next be described.

The load which is supported from the transverse bar of the lifting block will maintain the line taut when the load is being raised or lowered. However, as soon as the load is supported by any means whatsoever, the force exerted upon the lifting line by the load suddenly will decrease and the lifting line will become slack. The slackening of the line will decrease the force exerted through the lifting line on the tension weight. Consequently, the tension weight 8 will immediately descend under the force of gravity to take up the slack in the lifting line. The piston 12 will correspondingly move downwardly with the tension weight since the check valves 14 will be open as shown in Figure 1 to permit the hydraulic fluid to flow through the piston. As a result the resistance upon the piston by the hydraulic fluid will be negligible. Should the piston approach the lower end of the brake cylinder before the load acts upon the lifting line to tighten up the line, the switch 23 will be actuated and will stop rotation of the lifting drum. Therefore, even if the tension weight 8 cannot move further downwardly no additional slackening will occur in the lifting line.

When the full force of the load is again exerted upon the lifting line, the line will move the tension weight 8 upwardly. This upward movement of the tension weight will cause a corresponding upward movement of the piston 12. This upward movement of the piston will be considerably slowed, however, since the check valves 14 and 18 will be closed so as to prevent the circulation of fluid through the piston. Therefore, the tension weight 8 will slowly move upwardly until it is stopped by contacting the buffer stop 9. When the tension weight 8 contacts the buffer stop it will be moving at a rather slow speed because of the action of the braking cylinder and hence, there will be very little shock in the crane structure.

Proceeding next to the embodiment shown in Figure 2, the hydraulic braking cylinder and tension weight of Figure 1 is eliminated and a tension winch indicated generally at 24 is substituted therefor. The winch 24 is guided along a vertically extending rack 25 which is connected with the crane frame 1. The winch 24 has a pinion 26 which is in mesh with the rack 25. The pinion 26 is connected on a shaft 27 upon which is also connected a gear 28 which is engaged by a ratchet 29. The gear 28 is drivingly connected to a winch tension motor 30 through gearing indicated at 31.

In the operation of the embodiment in Figure 2, the entire tension winch 24 will move downwardly on the rack 25 when any slack occurs in the lifting line. However, when force is exerted on the lifting line by the load so as to cause an upward movement of the tension winch, the pinion 26 is connected with the tension motor 30 by the ratchet 29 and the gear 28 so that the upward movement is braked by the tension motor. This braking will occur throughout subsequent movement of the tension winch until the winch engages the buffer stop 9. Thus, it can be seen that the embodiment of Figure 2 functions in the same manner as the embodiment in Figure 1, except for the fact that in the Figure 2 embodiment braking is accomplished by a winch and in Figure 1 braking is accomplished by a hydraulic cylinder.

Various modifications may be made in each of the embodiments in Figures 1 and 2 without departing from the scope of the invention. For example, the hydraulic brake in Figure 1 could be replaced by a pneumatic brake. In addition, the invention is not restricted to stripper cranes but to any type of crane where there is any danger of a slackening in the lifting line.

Thus it can be seen that the tension maintaining device of the present invention is extremely simple in operation and requires little room since it is fastened on a downwardly directed end of the lifting line. The principal action of the tension maintaining device to eliminate

slack in the lifting line is under the force of gravity. This device will therefore act with extreme speed and with a minimum of delay and will prevent the accumulation of slack in the line. In those rare instances where 5 the slack occurs so suddenly that it cannot be properly eliminated by the device, the rotation of the lifting drum will be stopped under the action of a switch as previously described.

An additional advantage of this invention is the discovery that relatively low forces are necessary to prevent the slackening in a crane lifting line. The slack in the line is eliminated essentially by a stretching of the lifting line under the exertion of a pulling force by a tension element. Furthermore, the tension element is provided 15 with a braking device which so operates that the force exerted by the braking device on the lifting line during a slackening movement of the line is considerably smaller than the portion of the load acting upon the line, whereas during the movement of the lifting rope which tends to 20 stretch the rope, the power exerted by the braking device is almost equal to that portion of the load acting upon the lifting line end. In employing this tension maintaining device, the total weight of the crane is increased by only 25 a small amount but slackening of the crane line is effectively eliminated. Furthermore, the tension device is so related to the crane that there will be no undue rapid lowering of the load so as to endanger personnel or equipment. In all likelihood this would be the case if too little tension were exerted by the tension maintaining device 30 during any lowering of the load.

It will be understood that this invention is susceptible to modification in order to adapt it to different usages and conditions and, accordingly, it is desired to comprehend such modifications within this invention as may fall 35 within the scope of the appended claims.

What is claimed is:

1. In a crane, a lifting drum, a lifting pulley block, a line having one end wound around said lifting drum and the other end passing around said block pulley with said 40 other end of the line being directed downwardly, means on said line other end for exerting a pulling force on said line to maintain said line under tension, and a braking device connected to said tension maintaining means to exert a force considerably smaller than the load acting on the 45 rope when said rope other end is being moved in a direction which tends to stretch the same but which exerts a force almost equal to the load exerted on the lifting rope during the movement of the lifting rope which tends to slacken the rope.
2. In a crane, according to claim 1, wherein said braking device comprises a hydraulic pressure cylinder.
3. In a crane, a lifting drum, a pulley block, a lifting line having one end wound around said drum and the other end passing around said block pulley with said 55 other end being directed downwardly, a tension weight on said downwardly directed end to maintain said line under tension, and a brake attached to said tension weight for braking the upward movement of the tension weight but enabling the tension weight to move downwardly under the force of gravity.
4. In a crane, according to claim 3, with said brake comprising a cylinder, a piston slidably mounted within said cylinder and having one end attached to said tension weight, valve means interconnecting both sides of said 60 piston and operable only when said piston is moving upwardly so as to brake the upward movement of the tension weight but to open when said piston is moving downwardly to enable said tension weight to descend under the force of gravity.
5. In a crane, as claimed in claim 4, with said brake cylinder being connected to a balancing chamber which is open to the atmosphere.
6. In a crane, a lifting drum, a pulley block, a line having one end wound around said lifting drum and the other end passing around said pulley block with said other 75

end being directed downwardly, means on said other end of said lifting line movable upwardly and downwardly for exerting a pulling force on said line to maintain said line under tension, and a switch actuated by the downward movement of said tension maintaining means for stopping the operation of said lifting drum.

7. In a crane, a lifting drum, a lifting pulley block, a line having one end wound around said lifting drum and the other end passing around said block pulley with said other end of the line being directed downwardly, means on said line's other end and movable upwardly and downwardly for exerting a pulling force on said line to maintain said line under tension, and a braking device connected to said tension maintaining means to exert a

force considerably smaller than the load acting on the rope when said tension maintaining means is being moved in a direction which tends to stretch the same but which exerts a force almost equal to the load exerted on the lifting rope during the movement of the tension maintaining means which tends to slacken the rope.
